UNITED STATES PATENT OFFICE

109,765

DESIGN FOR A BRACELET

Mildred Oppenheim, New York, N. Y.

Application April 16, 1938, Serial No. 76,565

Term of patent 3½ years

To whom it may concern:

Be it known that I, Mildred Oppenheim, a citizen of the United States, residing at New York, in the county and State of New York, have invented a new, original, and ornamental Design for a Bracelet, of which the following is a specification, reference being had to the accompanying drawing, forming part thereof, wherein—

The figure is a perspective view of a bracelet showing my new design, the characteristic feature of which consists in the arrangement on a bracelet band of a plurality of multi-colored tooth picks or the like, substantially as shown.

I claim:

The ornamental design for a bracelet, substantially as shown and described.

MILDRED OPPENHEIM.
